US00D929357S

(12) **United States Design Patent** (10) **Patent No.:** **US D929,357 S**
(45) **Date of Patent:** **** Aug. 31, 2021**

(54) **MOBILE PHONE**

(71) Applicant: **BEIJING XIAOMI MOBILE SOFTWARE CO., LTD.**, Beijing (CN)

(72) Inventors: **Qi Guo**, Beijing (CN); **Yangyang Cai**, Beijing (CN); **Tao Jiang**, Beijing (CN); **Jiantao Zhang**, Beijing (CN); **Zhenhua Liu**, Beijing (CN)

(73) Assignee: **BEIJING XIAOMI MOBILE SOFTWARE CO., LTD.**, Beijing (CN)

(**) Term: **15 Years**

(21) Appl. No.: **35/509,483**

(22) Filed: **Nov. 29, 2019**

(80) **Hague Agreement Data**

Int. Filing Date: **Nov. 29, 2019**

Int. Reg. No.: **DM/205557**

Int. Reg. Date: **Nov. 29, 2019**

Int. Reg. Pub. Date: **May 29, 2020**

(30) **Foreign Application Priority Data**

Oct. 8, 2019 (CN) 201930545585.9
